UNITED STATES PATENT OFFICE.

FREDERICK J. MILLER, OF TOLEDO, OHIO, ASSIGNOR TO THE WESTERN GAS FIXTURE COMPANY, OF TOLEDO, OHIO, A CORPORATION OF OHIO.

HICKEY.

1,019,821.

Specification of Letters Patent. Patented Mar. 12, 1912.

Application filed November 25, 1911. Serial No. 662,525.

To all whom it may concern:

Be it known that I, FREDERICK J. MILLER, a citizen of the United States, and a resident of Toledo, in the county of Lucas and 5 State of Ohio, have invented a certain new and useful Hickey; and I do hereby declare the following to be a full, clear, and exact description of the invention, such as will enable others skilled in the art to which it 10 appertains to make and use the same, reference being had to the accompanying drawings, and to the figures of reference marked thereon, which form a part of this specification.

15 My invention relates to electric fixtures, and has for its primary object the provision of an improved form of hickey for use in connecting electric fixtures to the customary crow-foot or wall bracket or to an insulation 20 joint in such manner as to protect the electric wires of the fixture and to permit of a quick and easy installing of the same.

The invention is fully described in the following specification and a preferred embodiment thereof illustrated in the accompanying drawings, in which,—

Figure 1 is a side view of a side wall electric light fixture embodying my invention with parts in section and broken away. 30 Figs. 2 and 3 are different views of the hickey comprising the invention, and Fig. 4 is a side view of a fixture equipped with the invention and provided with an insulation joint.

35 Referring to the drawings, 1 designates the hollow arm or stem of the ordinary side wall electric fixture, 2 the hickey comprising my invention, which is shown in Fig. 1 as connecting the stem to the customary wall 40 bracket or crowfoot 3, and in Fig. 2 as connecting to an insulating joint 4, and 5 the canopy.

The hickey 2 comprises a short length of tubing, one end portion of which is externally threaded, as at 6, to adapt it to thread into the crowfoot 3 or insulating joint 4, as the case may be, while the other end portion thereof is externally enlarged to provide a shoulder 7 at the inner end of the threaded 50 portion 6, and is internally threaded to adapt a threading of the inner end of the stem therein. The threaded end 6 of the hickey is provided longitudinally thereof with a slot 8, which extends into the enlarged portion of the hickey or beyond the

shoulder 7 and has its inner end enlarged. This slot permits the wires 9, 9 to pass from the interior of the hickey and attach to the lead wires 10, 10 at a side of the crow-foot or joint, as is well understood in the art. 60 The wires 9, 9 are projected through the slot 8 before attaching the hickey to the crow-foot or joint and are intended to lie within the enlarged inner end of such slot during a screwing home of the hickey. The provision of the shoulder 7 intermediate the ends of the slot 8 provides a positive stop for limiting the screwing home of the hickey, thus preventing a cutting of the wires or injury to the insulation thereof by 70 reason of a pinching of the wires between the end of the slot and the part into which the hickey threads. This is a very important feature of my invention, as it prevents a short circuit at the point of projection of 75 the wires from the fixture, thus adapting it to meet the underwriters' requirements in this respect.

My improved hickey is found in practice to afford numerous advantages over the 80 methods heretofore employed in the hanging of electric fixtures, as it enables the hanger to first screw up the crowfoot, independent of the fixture, then by means of the improved coupling or hickey the fixture or 85 bracket stem is screwed into the crowfoot without a possibility of injuring the wires, making it unnecessary to have any more than barely room enough back of the canopy to make wire connections, thus doing away 90 entirely with the long sliding room formerly necessary on fixtures of this character, which often destroyed the grace and beauty of the design. In addition to the satisfaction of being able to do a much better job 95 with the use of my improved hickey, the time saved effects a very considerable saving in the cost of hanging such fixtures.

I wish it understood that my invention is 100 not limited to any specific construction or arrangement of the parts except in so far as such limitations are specified in the claims.

Having thus described my invention, what I claim as new, and desire to secure by Letters Patent, is,—

1. A single-piece hickey having its opposite end portions threaded and provided intermediate its ends with a shoulder for limiting the threading of a fixture part to one end thereof, such end having a longitudinally 110

extending wire-receiving slot therein which terminates at its inner end beyond said shoulder.

2. A single-piece hickey having its opposite ends threaded with at least one of such threads external and having a stop shoulder adjacent the inner end of the external thread, said externally threaded portion having a longitudinally extending slot

which has its inner end enlarged and terminating beyond said shoulder. 10

In testimony whereof, I have hereunto signed my name to this specification in the presence of two subscribing witnesses.

FREDERICK J. MILLER.
